PUMP SEAL

Leroy Albert Thomson, La Crosse, Wis., assignor
to Bump Pump Company, La Crosse, Wis., a
corporation of Wisconsin

Application September 26, 1938, Serial No. 231,669

2 Claims. (Cl. 286—7)

The present invention relates generally to improvements in the art of propelling fluids, and relates more specifically to improvements in the construction and operation of pumps for impelling liquids.

Generally defined, an object of my invention is to provide an improved pump assemblage which is simple and compact in construction and which is moreover highly efficient in use.

Some of the more specific objects of the invention are as follows:

To provide a pump especially adapted for use in industries such as the dairy industry, which is sanitary in use and which may be readily maintained in sanitary condition.

To provide an improved pump assemblage which is relatively leakproof even when operating upon relatively thin, oily or greasy liquids which are rather difficult to confine.

To provide a compact liquid pump which may be readily assembled and dismantled, and all parts of which are conveniently accessible for inspection, cleaning and replacement.

To provide a durable high pressure pump which is effectively sealed against possible escape of the fluid being pumped, and which requires minimum attention when in normal use.

To provide an improved self-sealing rotary shaft packing for pumps or the like, which may be quickly and conveniently applied or removed and all parts of which are readily accessible for cleaning.

To provide a new and useful pumping unit for liquid such as milk or cream, which is devoid of pockets, crevices or corners wherein solid substances are apt to accumulate and which are not readily accessible for cleaning.

To provide a positive displacement pump assemblage wherein the fluid impelling members or rotors, as well as their supports and driving members are readily accessible and removable.

To provide an improved pump driving assemblage in which the elements are firmly held in operating condition and cannot become dislodged during normal operation of the assemblage.

To provide an improved pump drive and leakage prevention seal.

To provide a simple pump structure which can be readily manufactured, and which is operable with minimum power consumption.

To provide a compact positive displacement pump assemblage of relatively large capacity, which may be manufactured and sold at moderate cost, and wherein the wear and tear has minimum deteriorating effect.

To provide an improved pump wherein undesirable churning of liquid such as oil or milk is eliminated in all portions of the assemblage.

To provide a dairy pump which fully meets the statutory and other requirements as to sanitation and health.

These and other specific objects and advantages will be apparent from the following detailed description.

A clear conception of embodiments of the various improved features constituting this invention, and of the mode of constructing and of operating rotary positive displacement pumps built in accordance with the improvement, may be had by referring to the drawing accompanying and forming a part of this specification wherein like reference characters designate the same or similar parts in the several views.

Fig. 1 is a part sectional side elevation of one of the improved pumps, the section being taken longitudinally and centrally through the structure;

Fig. 2 is an end elevation of the pump of Fig. 1, with a portion of the end closure or cover broken away to show the pump interior; and

Fig. 3 is an exploded or partially dismantled perspective view of one of the rotor, shaft and seal assemblages.

While the invention has been shown and described herein as having been embodied in a specific type of rotary positive displacement pump especially adapted for use in the dairy and ice cream industries, it is not the intent to thereby unnecessarily restrict the scope, since some of the improved features are obviously susceptible of more general application.

Referring to the drawing, the improved pump assemblage illustrated therein comprises in general a main pump housing or casing 5 having therein intercommunicable displacement chambers 6 with which inlet and outlet conduits 7 are directly communicable; a removable end closure plate or cover 8 coacting with a plane end face of the casing 5 to normally enclose the chambers 6; a pair of similar coacting positive displacement impellers 9, 10 concealed and rotatable within the chambers 6; laterally separated parallel rotor shafts 11, 12 journaled for rotation within bearings 13 formed integral with the casing 5 and having splined ends 14 coacting with grooved central bores 15 formed in the hubs 16 of the impellers 9, 10 respectively; an improved packing or sealing assemblage coacting with each of the shafts 11, 12 at its point of exit or projection from within the casing 5; a pro-

elling or driving shaft 17 for each rotor shaft 11, 12 journaled in anti-friction bearings 18, 19 mounted in inner and outer gear casings 20, 21 respectively, the former of which is rigidly attached to the pump casing 5 and the latter of which is removably secured to the inner gear casing 20; sleeve couplings 22 connecting the driving shafts 17 with the adjacent aligned ends of the rotor shafts 11, 12; and motion transmitting gears 23, 24 removably secured to the shafts 17 by means of Woodruff keys 25 and intermeshing with each other to impart simultaneous but opposite rotation to the impellers 9, 10 when power is applied to the projecting end of the upper driving shaft 11.

The main pump casing 5 and bearings 13 are preferably formed integral, but the bearings 13 may be provided with wearing bushings if so desired, and the inner gear casing 20 may be firmly attached to the end of the casing 5 remote from the cover 8, by means of dowel pins 26, or otherwise. The space between the casings 5, 20 is preferably open at the opposite sides so as to permit free access to the rotor shaft seals and to the couplings 22. Since the improved pump is operable in either direction and is therefore reversible, either of the conduits 7 may be utilized either as an inlet or outlet, and the conduits 7 which are formed integral with the casing 5 are threaded or otherwise formed for convenient attachment to the fluid conducting pipes of the system with which the pump cooperates.

The displacement chambers 6 within the main casing 5 are of generally semi-cylindrical shape, and the lobes of the impellers 9, 10 are formed to snugly engage the surfaces bounding the chambers 6 and the casing bearings 13 with minimum clearance. The coacting corners of the casing 5 and of the impellers 9, 10 are preferably slightly rounded as shown, in order to prevent undesirable accumulation of solids in these corners, and also so as to facilitate cleaning, this being an important feature. The impellers 9, 10 besides being firmly drivingly connected to their respective shafts 11, 12 by means of the splined ends 14, are retained upon these shafts by end collars 27 which may be rigidly attached to the reduced shaft ends in any suitable manner. The end closure or cover 8 is provided with bored pockets 28 formed for snug reception of the rotor hubs 16 and collars 27, and these bores provide bearings for the impellers 9, 10 and are also rounded at the corners which coact with the rotors so as to prevent accumulation of solids and to facilitate cleaning. The cover 8 is adapted to be removably attached to the plane end face of the pump casing 5 to snugly confine the impellers 9, 10 in operative condition, by means of wing nuts 29 coacting with studs 30 secured to the main casing 5. The external surfaces of the housing elements including the casing 5, cover 8, and gear casings 20, 21 are also preferably rounded at all convex and concave corners so as to prevent accumulation of dirt and to facilitate cleaning, thereby providing an extremely sanitary assemblage.

The improved packing or sealing assemblages which are provided at the points of protuberance of the rotor shafts 11, 12 from the casing 5, are of like and interchangeable construction, and are freely accessible through the large side openings communicating with the space between the casings 5, 20. Each of these seals comprises

a coil spring 31 confined within a bore 32 in the casing 5 and coacting with this casing and with a metallic seating ring 32' which coacts with one side of a pliable packing ring 33 slidably confined in the bore 32; a non-rotary ring 34 embracing the rotor shaft and supporting the rings 32', and having pins 35 coacting with slots 36 in the casing 5 so as to prevent rotation of the ring 34 while permitting slight displacement thereof along its own axis; a tapered sealing ring 37 coacting with the plane and face of the ring 34 and having peripheral notches 38; another oppositely tapered sealing ring 39 spaced from the ring 36 and having peripheral pins 40 slidably cooperable with the notches 38 of the ring 37; a pliable packing ring 41 confined between the tapered sides of the rings 37, 39 and snugly engaging the corresponding rotor shaft; and a U-shaped retaining element 42 formed for snug engagement with opposite flat notches 43 of the rotor shaft and having diametrically opposite peripheral notches 44 cooperable with the pins 40 to revolve the rings 37, 39, 41 with the rotor shaft. The ends of the shafts 11, 12 outwardly beyond the sealing assemblages, are provided with longitudinal recesses 45 with which internal projections 46 of the couplings 22 coact and the driving shafts 17 also have grooves 47 engageable with the projections 46 to complete the driving connection. The packing assemblage is obviously such that the spring 31 will constantly urge the corresponding pump impeller 9, 10 and shaft 11, 12 into snug contact with the casing 5 and away from the cover 8, and when the end cover 8 and the retaining elements 42 are removed and the springs 31 are released, the impellers 9, 10 with their supporting and driving shafts 11, 12 may be slid freely and axially from within the casing 5, and the sealing elements 35, 36, 37, 39, 41 are no longer locked and will permit free withdrawal of the shafts 11, 12 therefrom as will be evident from Fig. 3.

The gear housings or casings 20, 21, are detachably interconnected by means of cap screws 48, and form a gear enclosing chamber 49 which may be supplied with suitable lubricant such as grease. The ball or other anti-friction bearings 18, 19 for the driving shafts 17 are exposed to the chamber 49, and in order to prevent escape of lubricant, the casing 20 is provided with a packing 50 adjacent the bearing 18 and coacting with the sleeve coupling 22, while the closure casing 21 is provided with a similar packing 51 embracing the driving shaft 17 which projects outwardly therebeyond. Power may be applied to the projecting driving shaft 17 from any convenient source, and the motion transmitting gears 23, 24 may be of any desirable type; and the shafts 17 and gears 23, 24 are normally retained in proper position and prevented from axial shifting by means of spacer sleeves 52, 53 coacting with the inner races of the bearings 18, 19 respectively and with the opposite faces of the gears. It is to be noted that all of the transmission elements are readily accessible upon removal of the cover casing 21 and the sleeves 52, 53 which positively prevent axial displacement of the shafts 17, permit these shafts to absorb the end thrust exerted by the springs 31 upon the aligned rotor shafts 11, 12.

When the several elements of the pump have been properly manufactured, the structure may be readily assembled and dismantled at any time. The casings 5, 20 are normally rigidly united and

require no separation. The rotors 9, 10 and the shafts 11, 12 must be frequently removed and reassembled, while the shafts 17 and gears 23, 24 are rarely removable. During the assembly of the structure, the rotors 9, 10 should first be properly secured to their respective shafts 11, 12 whereupon these shafts may be inserted within the bores of the bearings 18 until the ends of the rotor shafts protrude slightly beyond the packing recesses or bores 32. The springs 31 may then be inserted within the bores 32 over the ends of the shafts 11, 12. The spring seating rings 32' and pliable packing rings 33 may then be applied to the rings 34 and inserted within the bores 32 with the rings 32' in contact with the springs 31, and the pins 35 should be caused to coact with the slots 36. The rings 37, 41 and 39 may then be applied to the shafts 11, 12 in succession, and with the pins 40 in engagement with the notches 38. The retaining elements 42 may thereafter be applied to the notches 43 of the shafts 11, 12 by compressing the springs 31 sufficiently to cause the pins 40 to permit insertion of the elements 42. Upon subsequent release of the springs 31, these springs will force the sealing rings 33, 41 into the position shown in Fig. 1 and the assemblage will thus be retained by the elements 42. The shafts 11 to which the gears 23, 24 are firmly attached and which are rotatably supported in the bearings 16, 19 are fixed against longitudinal displacement by the sleeves 52, 53; and when the springs 31 expand, they cause the rotor shafts 11, 12 to enter the couplings 22 secured to the shafts 17 and to abut against the ends of the corresponding shafts 11, thereby completing the driving connections. Dismantling of the assemblage may be readily accomplished by merely reversing the assembly operations, and if it becomes necessary to dismantle the gear and drive shaft assemblage, the cover casing 21 may be removed.

During normal operation of the pump, power may be applied to the outer end of the protruding shaft 17 to cause the gears 23, 24, to simultaneously rotate in opposite directions. While the primary driving shaft 17 will transmit rotating motion directly to the pump impeller 9, simultaneous but opposite rotation will be imparted to the other pump impeller 10 through the gears 23, 24 and the other driving shaft 11. Depending upon the direction of rotation of the driving shaft 17, the impeller 9, 10, may cause fluid to be drawn through one of the conduits 7 and delivered through the other conduit. While the general type of impellers 9, 10, used in the pump are old and well known, it is an important feature of the present invention that the corners of the impellers 9, 10 are rounded and coact with the rounded corners in the casing 5 and cover 2. This rounding will obviously initially prevent undesirable accumulation of solids in these corners, and will permit thorough cleaning of the corners when the structure is dismantled. This is extremely important when pumps of this type are used to propel greasy liquids such as milk and cream and the improved pump may therefore be readily maintained in sanitary condition.

When the pump is operating normally, any leakage fluid under pressure which escapes from the chamber 6 along the shafts 11, 12, will tend to escape through the chambers formed by the bores 32. The compression springs 31 coacting with the seating rings 32' and with the pliable rings 33 will force these rings 33 into intimate

5 contact longitudinally along the bores 32 thereby producing perfect sealing against escape of fluid longitudinally of the shafts 11, 12. The leakage fluid at each packing cannot escape past the ring 33 and therefore endeavors to escape between the bore of the ring 34 and the corresponding shaft 11, 12. The ring 37 coacting with the ring 34 however provides a sealed rotary joint which prevents escape of the leakage fluid between these rings, and the pliable packing ring 41 which is compressed by the spring 31 between the sealing rings 37, 39 positively prevents escape of the leakage fluid beyond the ring 37. The seating rings 32' serve to equalize and 10 to distribute the spring pressure upon the pliable rings 33 with which they coact, and thus produce uniform expansion of the rings 33 and of the sealing assemblages. It will thus be noted that the improved seals will effectively prevent escape of any fluid from within the chamber 6, and the construction of the packing elements is obviously such that no churning of liquid which may escape into the bores 32, can possibly occur. The packing rings 33, 34 and the spring 31 do not rotate, and the rotatable rings 37, 39, 41 have no protuberances which will tend to churn the fluid engaging the same. The sealing assemblages cooperate with the rotor shafts 11, 12 and impellers 9, 10 to prevent undesirable wear on the other faces of the rotors, and the wear on the inner rotor faces and on the rings 33, 37 is automatically compensated for by the springs 31 which do not rotate.

15 The packing elements may however be readily removed over the ends of the shafts 11, 12 when these ends are withdrawn from the couplings 22 and the seals also eliminate wear in these couplings by eliminating relative movement between the shafts 11, 12 and the coupling sleeves during normal operation. The ends of the shafts 11, 12 remote from the impellers 9, 10 have no outward projections, and the driving connection is obtained by the use of recesses 45 coacting with inward projections 46 on the sleeve couplings 22. While the U-shaped retainers 42 provide suitable means for holding the sealing assemblages in place during normal operation, these retainers may obviously be formed integral with the adjacent rings 39 and secured to the shafts 11, 12 by locking means other than the slots 43, such as radial pins coacting with lateral inclined extensions of the shaft grooves 45. The impellers 9, 10 and the shafts 11, 12 cannot, however, be removed without first releasing the locking retainers, and the shafts 17 and gears 23, 24 are not disturbed by removal of the impellers. The transmission gearing may obviously be abundantly lubricated and is normally effectively confined within the casing 20, 21, but may be removed if necessary. Escape of lubricant from the transmission chamber 49 is positively prevented by the packings 50, 51 and the gears 23, 24 as well as the shafts 17 are prevented from shifting endwise by the two sleeves 52, 53 and gears 23, 24 coacting with the bearings 16, 19.

20 From the foregoing specific description it will be apparent that the present invention provides an improved pump assemblage which is simple, compact and durable in construction and which is highly efficient and sanitary in use. All parts of the assembly are conveniently accessible for cleaning and inspection, and by virtue of the fact that all parts of one pump impeller assemblage are interchangeable with similar parts of the other, the cost of construction and assem-

blage may be reduced to a minimum. The improved pump is obviously effectively sealed against possible escape of liquid by efficient packings coacting with the shafts 11, 12, and these sealing devices also reduce wear to a minimum and may be readily assembled or removed and cannot churn liquid which comes in contact with the elements thereof. The various elements of the assemblage are so constructed that the pump cannot possibly be improperly assembled, and the device may therefore be dismantled and re-assembled by a novice. The improved pump assemblage has proven highly satisfactory in actual commercial use, and is obviously especially applicable to the dairy industry.

It is to be understood that it is not desired to limit this invention to the exact details of construction or to the precise mode of use, herein shown and described, for various modifications within the scope of the claims may occur to persons skilled in the art.

I claim:

1. In combination, a casing having a bearing and an enlarged bore adjoining said bearing opening outwardly of the casing, a shaft journalled in said bearing and extending outwardly of said casing through and beyond said bore and having diametrically opposite transverse notches therein remote from the open end of said bore, a U-shaped retaining element slidably coacting with said shaft notches to fixedly secure the element to said shaft, said element having peripheral grooves extending longitudinally of said shaft, an outer rotary ring embracing said shaft between said element and said bore and having driving pins projecting from the opposite sides of the ring and coacting with said element grooves, an inner rotary ring embracing said shaft between said outer ring and said bore and having peripheral recesses slidably and drivingly engaged by said pins, an inwardly distortable pliable packing snugly embracing said shaft between said rings, a non-rotary ring slidably confined within said bore and having an end face in sealing engagement with the adjacent end face of said inner rotary ring, means for posi-

tively preventing rotation of said non-rotary ring while permitting free sliding thereof along said bore, an outwardly distortable pliable packing carried by said non-rotary ring and snugly engaging said bore, and resilient means within said bore and coacting with the bore bottom and with said outwardly distortable packing to distort said packings and to urge said rings toward each other and against said element.

2. In combination, a casing having a bearing and an enlarged bore adjoining said bearing opening outwardly of the casing, a shaft journalled in said bearing and extending outwardly of said casing through and beyond said bore and having diametrically opposite transverse notches therein remote from the open end of said bore, a U-shaped retaining element slidably coacting with said shaft notches to fixedly secure the element to said shaft, said element having peripheral grooves extending longitudinally of said shaft, an outer rotary ring embracing said shaft between said element and said bore and having peripheral recesses slidably and drivingly engaged by said pins, an inwardly distortable pliable packing snugly embracing said shaft between said rings, a non-rotary ring slidably within said bore and having a plane end face in sealing contact with the adjacent plane end face of said inner rotary ring, radial projections carried by said non-rotary ring and slidably engaging said casing to positively prevent rotation of said non-rotary ring while permitting free sliding thereof along said bore, an outwardly distortable pliable packing carried by said non-rotary ring and snugly engaging said bore, and a spring embracing said shaft within said bore and coacting with said casing and with said outwardly distortable packing to distort said packings and to urge said rings toward each other and against said element.

LEROY ALBERT THOMSON.
